At this

UNITED STATES PATENT OFFICE.

C. WILLIAM KRAUSE, OF CHICAGO, ILLINOIS.

DRIVE-CHAIN.

SPECIFICATION forming part of Letters Patent No. 379,115, dated March 6, 1888.

Application filed August 9, 1887. Serial No. 246,498. (No model.)

To all whom it may concern:

Be it known that I, C. WILLIAM KRAUSE, a subject of the Emperor of Germany, residing at Chicago, in the county of Cook and State of Illinois, have invented a new and useful Improvement in Link Belts, of which the following is a specification.

My invention relates particularly to an improvement in the construction of the links of belts or drive-chains, it being my object to provide a construction of link to reduce the quantity of material required to form it and the friction or grinding effect in its use upon the joints of the belt or chain formed by connecting several together, which effect is so great, by comparison, in link belts known to me of constructions differing from my present improvement that it entails rapid wearing of the belts, thus adding materially to the cost of running machinery involving them.

My invention consists in the general construction of my improved device; and it also consists in details of construction and combination of parts, all as hereinafter more fully set forth.

In the drawings, Figure 1 is a plan view of a section of a belt formed according to my improved construction, and showing two of my improved links connected together; Fig. 2, a side view of the same, having a portion of a link broken away to display a detail of construction; Fig. 3, a view showing two links, one in broken sectional side elevation and the other by dotted lines in side elevation, joined together and presenting a modified construction of link; Fig. 4, a plan view of one side of a link of the modified construction, broken from the opposite side; Fig. 5, a rear end view of one of the links, and Fig. 6 a section taken on line 6 6 of Fig. 1 and viewed in the direction of the arrows:

A A are links, both of the same construction and each comprising a cross-head, r , enlarged at its extremities and provided on the upper side of each enlarged end with a rectangular recess, q , formed transversely to the cross-head and leading into a socket, p , below it, of greater diameter than the recess q , and flaring from or from near its center toward its extremities. From the forward sides of

the enlarged ends of the cross-head and from near the bases of the same extend parallel arms o and o' , bent slightly upward from the cross-head throughout a part of their lengths, thence straight to be in line with the sockets p . The bent portion of the arms o may be of any desired form in cross-section, whether round, square, or otherwise, and the ends are provided with heads n , either in the form shown in Figs. 1 and 2 or in the globular form illustrated in Figs 3 and 4. Behind the heads n the arms are cylindrical, as shown at x , and of a diameter to fit into sockets p , which diameter may correspond with or be greater or smaller than that of the arms toward their rear ends; and behind the cylindrical portions x the arms are flattened on the sides, as shown at m , to reduce their diameter sufficiently to permit them to be inserted through the recesses q into the sockets p .

To connect links A to form an endless belt the reduced parts m of the arms of one link are inserted into the sockets p through the recesses q at the ends of the cross-head r of another link, when the inserted link is drawn back to bring the parts x into the sockets p , wherein they are prevented from removal, unless in the reverse manner to that by which they are adjusted, by the stops afforded by the heads n and by the increased diameter of the parts x over that of the recesses q .

Of course a suitable number of links A are adjustable together in the manner described to produce an endless belt of desired length.

It will be seen that inasmuch as the strain exerted on the belt, when in use, is lengthwise of it, the links are not liable to become separated, and there can be but little wear by friction or grinding, since the heads n are rounded and rock against the sockets, which rocking motion is permitted by the flaring form of the sockets, and that the connection of one link to another may be readily accomplished, since to do so requires but the insertion of the parts m of one link at the recess q of another, and pulling them in opposite directions to bring the parts x into the sockets p .

If the ball form of head n shown in Figs. 3 and 4 is employed, I provide lateral flanges or ribs l on the arms near the sockets p , to guide

the heads *n* to the latter, and groove the sockets out at their inner ends, as shown at *y*, to form seats for the globular heads.

Of course I do not limit myself to the exact forms of heads *n* shown, as other forms may answer the purpose and are within the spirit of my invention. The degree of flaring of the sockets *p* also depends on the transverse thickness of the enlarged ends of the cross-heads. If these ends are sufficiently thin, the sockets may be straight, though of a diameter to permit the slight play required for the parts inserted into them.

What I claim as new, and desire to secure by Letters Patent, is—

1. A link belt formed of links A, all of similar construction, and comprising, each, arms *o* and *o'*, extending from opposite ends of a cross-head, *r*, and provided with heads *n* at their disconnected extremities and reduced portions *m*, recesses *q* in the cross-head, near opposite ends thereof, and sockets *p* in the cross-head of greater diameter than the recesses, and into which the recesses lead, whereby the links may be connected to form a chain and held against separation by introducing the reduced portions *m* of one link into the sockets *p* through the recesses *q* of another link, and drawing the parts of the arms in advance of the said reduced portions into the said sockets, substantially as described.

2. A link belt formed of links A, all of similar construction, and comprising, each, arms *o* and *o'*, extending from opposite ends of a cross-head, *r*, and provided with heads *n* at

their disconnected extremities and laterally-flattened reduced portions *m*, recesses *q* in the cross-head, near opposite ends thereof, and flaring sockets *p* in the cross-head of greater diameter than the recesses, and into which the recesses lead, whereby the links may be connected to form a chain and held against separation by introducing the reduced portions *m* of one link into the sockets *p* through the recesses *q* of another link, and drawing the parts of the arms in advance of the said reduced portions into the said sockets, substantially as described.

3. A link belt formed of links A, all of similar construction, and comprising, each, arms *o* and *o'*, extending from opposite enlarged ends of a cross-head, *r*, and provided with rounded heads *n* at their disconnected extremities, laterally-flattened reduced portions *m*, and flanges *l*, recesses *q* in the enlarged ends of the cross-head, and flaring sockets *p* in the said enlarged ends, hollowed out at their inner extremities to afford seats *y*, and into which the said recesses lead, whereby the links may be connected to form a chain and held against separation by introducing the reduced portions *m* of one link into the sockets *p* through the recesses *q* of another link, and drawing the parts of the arms in advance of the said reduced portions into the said sockets, substantially as described.

C. WILLIAM KRAUSE.

In presence of—

CHAS. E. GAYLORD,

J. W. DYRENFORTH.
